Specification for Design.

Patented June 29, 1920.

Application filed December 13, 1919. Serial No. 344,705. Term of patent 7 years.

To all whom it may concern:

Be it known that I, FREDERICK KAUPMANN, Jr., a citizen of the United States, residing at Brooklyn, county of Kings, State of New York, have invented a new, original, and ornamental Design for Hatpins, Scarf-pins, Cuff-Links, Tie-Clips, Rings, Fobs, Pendants for Neck-Chains, Pins, or Articles of Manufacture of like Character, of which the following is a specification, reference being had to the accompanying drawing, forming a part thereof.

The drawing is a plan view of a pin, pendant, or similar article of manufacture embodying my new design.

I claim:

The ornamental design for a hatpin, scarf pin, cuff link, tie clip, ring, fob, pendant for neck chains, pin, or article of manufacture of like character as shown.

FREDERICK KAUPMANN, JR.
